UNITED STATES PATENT OFFICE.

WALLACE B. CURTIS, OF HAMBURG, NEW YORK.

GARMENT-STRETCHER.

1,208,506.

Specification of Letters Patent. Patented Dec. 12, 1916.

Application filed November 17, 1915. Serial No. 61,987.

To all whom it may concern:

Be it known that I, WALLACE B. CURTIS, a citizen of the United States, residing at Hamburg, in the county of Erie and State 5 of New York, have invented new and useful Improvements in Garment-Stretchers, of which the following is a specification.

The invention relates to garment stretchers, and more particularly to the class of 10 trousers stretchers.

The primary object of the invention is the provision of a stretcher of this character wherein trousers can be conveniently and easily fastened therein and thereafter 15 stretched to the desired degree for rendering the same smooth and for effectively creasing the same.

Another object of the invention is the provision of a stretcher of this character where- 20 in the construction thereof is novel in form so that different sizes of trousers can be conveniently clamped therein and effectively stretched for removing wrinkles and creasing the same.

25 A further object of the invention is the provision of a stretcher of this character which is extremely simple in construction, thoroughly reliable and efficient in its opera- tion, strong, durable and inexpensive in manufacture.

With these and other objects in view, the invention consists in the features of construction and the combination and arrangement of parts hereinafter described, point- 35 ed out in the claim, and illustrated in the accompanying drawings.

In the drawings: Figure 1 is a plan view of a stretcher constructed in accordance with the invention, showing trousers there- 40 in; Fig. 2 is an edge elevation; Fig. 3 is a sectional view on the line 3-3 of Fig. 1; Fig. 4 is a sectional view on the line 4-4 of Fig. 1; and Fig. 5 is a sectional view on the line 5-5 of Fig. 1.

45 Similar reference characters indicate corresponding parts throughout the several views in the drawings.

Referring to the drawings in detail, the trousers stretcher comprises a pair of clamps 50 A and B respectively, each being formed in two sections 10 and 11, through which are passed bolt members 12, the same carrying winged nuts 13 so that the sections can be readily and conveniently brought into 55 clamping relation to each other, the bolt

member 12 being passed therethrough near opposite ends of the same. The sections 10 and 11 of each clamp at one end thereof are formed with bifurcations or slots 14 opening through the end edges of said sections 60 and the bolt members 12 passed therethrough are pivotally supported, as at 15, upon the sections 11 so that they can swing laterally from within the slot on the loosening of the nuts thereon, and thus in this 65 manner permitting the convenient placing of the trousers 16 in position between the sections 10 and 11 of the clamp.

The inner faces of the sections 10 and 11 of the clamp have suitably fixed thereon 70 anti-slipping strips 17 so that when the said sections are brought together for the clamping of the trousers the same will be prevented from slipping from between the said sections of the respective clamps A and B 75 of the stretcher.

Mounted in the section 11 of the clamp A are the limbs of a U-shaped frame 18, while slidably fitted upon the limbs of said frame is the section 11 of the clamp B so that the 80 latter section is movable relatively to the clamp A, and in this manner trousers of different lengths can be held within the stretcher and effectively stretched.

Secured to the section 11 of the movable 85 clamp B, medially thereof, is a leaf spring 19 formed with elongated openings 20, through which are loosely passed the limbs of the frame 18, and the walls of these openings 20 are adapted to coact and engage in ratchet surfaces 21 formed on the limbs of the frame 18 so that on the movement of the clamp B in one direction the springs will be automatically engaged with the ratchet surfaces 21 on the limbs of the 95 frame 18, and thereby lock the movable clamp in its adjusted position.

Secured to the section 11 of the clamp B is a hand-hold 22, which permits the manual adjustment of the movable clamp on the 100 frame 18, and when it is desired to release the movable clamp the ends 24 of the spring 19 are pulled outwardly away from the section 11 of the said clamp B, thereby freeing the same to permit the adjustment thereof 105 on the frame.

From the foregoing description, taken in connection with the accompanying drawings, the construction and manner of use of the device will be apparent, and a more 110

extended explanation has, therefore, been omitted.

Having thus described my invention, I claim:

- 5 A garment stretcher comprising a U-shaped frame formed from a single strand of stiff wire, pairs of clamping cleats, one cleat of one pair being fixed to the end of the frame, one cleat of the other pair being
10 slidable on the frame, adjustable bolts connecting the cleats of the pairs together, a pivot swingingly connecting one bolt to one cleat in each pair, the said cleats of both pairs being slotted to receive the swinging
15 bolts, a bowed leaf spring connected medially thereof with the cleat slidable on the

frame and having holes loosely receiving the frame, and ratchet teeth formed on the inner sides of the limbs of the frame and coacting with the edges of the holes in the springs for locking engagement thereof with the frame, the spring being fixed to the side of the slidable cleat facing the fixed cleat so that pulling action by the garment upon the slidable cleat will cause the biting engagement of the 25 spring with the teeth.

In testimony whereof I affix my signature in presence of two witnesses.

WALLACE B. CURTIS.
